UNITED STATES PATENT OFFICE.

JOHN S. COCHENNOUR AND NOAH T. REMY, OF OLNEY, ILLINOIS, ASSIGNORS
TO THE OLNEY VEHICLE SPRING SUPPORT MANUFACTURING COMPANY,
OF SAME PLACE.

VEHICLE-SPRING SUPPORT.

SPECIFICATION forming part of Letters Patent No. 446,203, dated February 10, 1891.

Application filed June 13, 1890. Serial No. 355,336. (No model.)

To all whom it may concern:

Be it known that we, JOHN S. COCHENNOUR and NOAH T. REMY, citizens of the United States, and residents of Olney, in the county 5 of Richland and State of Illinois, have invented certain new and useful Improvements in Vehicle-Spring Supports, of which the following is a specification.

Our invention relates to a vehicle-spring support, and more particularly to improvements in the device patented by one of us (John S. Cochennour) April 17, 1888, No. 381,111, all of which will be fully hereinafter described, and clearly pointed out in the 15 claims.

In the accompanying drawings, Figure 1 is a longitudinal elevation of an ordinary elliptical spring, showing our improvement applied thereto in its normal condition at rest; 20 Fig. 2, a longitudinal sectional elevation on line xx of Fig. 3 of our invention in its preferred form; Fig. 3, an end elevation of the device embodying our present improvement; Fig. 4, a transverse section of our device on line yy of Fig. 2; Fig. 5, a top plan view of 25 one of the circular holder-sockets or annular cases for containing one end of the spiral spring forming part of our device, the spring being omitted in this view; Fig. 6, a bottom 30 plan view of the holder-socket shown in Fig. 5; Fig. 7, a perspective view of a modified form of holder-socket, showing a detachable inclined seat for the said spiral spring; Fig. 8, a longitudinal sectional elevation of the 35 modification shown in Fig. 7 with the detachable inclined seat in place; Fig. 9, a view similar to Fig. 8, but of another modification; Fig. 10, a view also similar to Fig. 8, with the fastening-ears omitted; and Fig. 11, a plan 40 view of our preferred form of spiral spring for use in connection with our holder-socket.

A and A' represent the two members or sets of plates forming an ordinary elliptical spring, connected at their opposite ends as 45 customary, and having interposed between them, intermediate said ends, an upright auxiliary elastic support composed of a spiral spring B and annular cases or sockets C C',

the latter receiving and holding the opposite ends of said spiral spring.

c' represent flat ears or lugs constructed on each of said holder-sockets, constituting firm bases or foundations therefor, and c^2 represents holes in said ears for receiving the fastening bolts or screws c^3 .

The inner face of the bottom of each of the holder-sockets C C' is inclined circularly, or, in other words, the bottom of each is so constructed that it gradually increases in height or thickness in a circular path, beginning 60 with the point lettered a in Figs. 4, 5, and 7 and ending with the point lettered a' in Figs. 2, 4, 5, 7, 8, and 9, leaving a suitable space or opening between them (said points) which leads to a hole b in the socket-wall, through 65 which hole passes the outwardly-bent end b' of the said spiral spring. The inclination or pitch of the inner faces of said socket-bottoms is the same as that on which the spiral spring used therein is coiled, and the under side of 70 both said bottoms is flat, so that they may be properly secured in place on the inner faces of the several members of said elliptical spring.

In Figs. 2 and 11 we have clearly shown 75 how our spiral spring is preferably constructed for use in said holder-sockets. The opposite ends b' b' of said spring (for a half inch, more or less) are bent or turned outwardly at right angles with the main portion or body thereof 80 without disturbing the pitch of the coil, and when the spring is in place between two holder-sockets said bent ends practically form hooks or stops, whereby it is properly held in such place free from accidental turning or displacement. When spring B is placed in said 85 holder-sockets or seat-cups, its bent ends b' b' are inserted in their several holes b , which latter immediately succeed the thinnest or shallowest portions of said inclined bottoms, thus 90 bringing the upper and lower coils of said spring into registering contact with said inclined bottoms and forming a substantial support or rest in both directions vertically, whereby the upright and proper working position of 95 said spring is readily maintained. Said ends

b' b' project beyond their holes *b* just sufficient to secure a proper hold or bearing therein and do not interfere with the bolts or screws which are used for securing the device 5 in place.

It will be seen that the holder-sockets may be made of any suitable depth to accommodate the upper and lower portions of spring B, but we prefer that they shall each take in 10 at least three coils for the proper seating of said spring and effectually supporting it upright, free from any unnecessary play or movement in a lateral direction.

In the modifications shown in Figs. 7, 8, and 15 10 the bottom of the holder-socket is made of a constant or even thickness throughout, and we insert or apply a detachable or false bottom D, which is made in the form of a washer or ring having a radial opening or blank 20 space therein and constructed of gradually-increasing thickness from point *a* to point *a'*, as hereinbefore described. This detachable inclined bottom or washer is tapered or inclined on its upper face only, being flat on 25 its lower face to correspond and register with the flat horizontal upper face of the socket-bottom, said inclined upper face taking the same pitch as that on which the spiral spring supported thereby is coiled, thus adapting the 30 socket or collar to receive and support in an upright position spiral springs of various pitches, which is a very important feature.

In the modification shown in Fig. 9 we have 35 illustrated the manner in which each of the collars or sockets C C' may be constructed without a bottom, the elliptical spring itself forming a support for each of the detachable inclined false bottoms or washers, and they in turn supporting the spiral spring, as before 40 stated.

In the modification shown in Fig. 10 we 45 have illustrated the manner in which the fastening-ears for the holder-socket may be dispensed with and its bottom used as an attaching medium. In this case the upper part of the shank of the fastening-bolt *c* is made angular and fits within a correspondingly-angular opening at the center of said socket-bottom, thus preventing the unnecessary turning 50 of said sockets. The holes *b* for receiving the outwardly-bent ends or extensions *b'* of the spiral spring are also present in all the modifications; but in the modification shown 55 in Fig. 9 the hole *b* is extended or developed into a slot for the accommodation of the projecting end of the coil-spring.

In the operation of our device wherever applied it is obvious that every coil of the spiral spring is utilized, as no part thereof whatsoever 60 is ever encumbered, and the opposite end coils being provided with continuous and substantial bearings in deep sockets a suitable number of the coils of said spring at both its

ends serve to sustain it in an upright position at all times for said operation. 65

It is obvious that our device can be very readily applied or detached as occasion may require and also very economically made.

It will be understood that we do not intend to restrict ourselves to the precise details of 70 construction herein shown and described, but reserve the right to make all changes and to employ all mechanical expedients that come within the scope of the appended claims.

We claim as our invention—

1. In a vehicle-spring support, the combination, with a spiral spring having at its opposite ends the outwardly-turned extensions or hooks *b' b'*, of a pair of holder-sockets or annular cases C C', having transverse holes *b b* for the reception of said extensions or hooks, and the plane inner faces of their bottoms constructed at an inclination or gradually-increasing height or thickness in a circular line or path beginning and ending at 85 said holes *b*, whereby a firm and suitable seat is provided at both ends of said spring which registers or corresponds in pitch with the pitch on which the spring is coiled, substantially as herein set forth. 90

2. In a vehicle-spring support, a plane-faced filling and seating ring or washer constructed of gradually-increasing thickness or inclined upwardly, beginning with the thinnest end or point *a* and terminating with the heaviest end 95 or point *a'*, having a suitable space or opening between said ends *a* and *a'* for the accommodation of an outwardly-turned extension *b'* on the contained spiral spring and adapted to fit within a holder cup or socket, 100 substantially as and for the purpose specified.

3. In a vehicle-spring support, the spiral spring B, having its opposite ends *b' b'* turned or bent outwardly at right angles with its body without disturbing the pitch on which 105 it is coiled, substantially as and for the purpose specified.

4. The combination, with an elliptical spring, of the internal auxiliary spiral spring B and the holder sockets or cups C C', the latter having transverse holes *b b* and the plane inner faces of their bottoms constructed on an incline beginning and ending at said transverse holes in a circular line or path to form suitable receptacles and seats or bearings, respectively, for the opposite ends and extensions *b'* of said auxiliary spring, substantially in the manner and for the purpose herein set forth. 115

In testimony of which invention we have 120 hereunto set our hands.

JOHN S. COCHENNOUR.
NOAH T. REMY.
